CLAIM

The ornamental design for a trim molding for a motor vehicle window, as shown and described.

DESCRIPTION

FIG. 1 is a front perspective view of a trim molding for a motor vehicle window, showing our new design; and,

FIG. 2 is a right end view thereof.

The middle portion of the trim molding is broken away in FIGS. 1 to indicate no particular length. The broken lines in FIGS. 2 show a window edge and form no part of the claimed design.
